ATTORNEY'S

UNITED STATES PATENT OFFICE.

CHARLES W. KALLENBAUGH, OF DUQUESNE, PENNSYLVANIA.

TOY PISTOL.

1,187,065.

Specification of Letters Patent. Patented June 13, 1916.

Application filed February 27, 1915. Serial No. 11,056.

To all whom it may concern:

Be it known that I, CHARLES W. KALLENBAUGH, a citizen of the United States, residing at Duquesne, in the county of Allegheny and State of Pennsylvania, have invented certain new and useful Improvements in Toy Pistols, of which the following is a specification.

This invention relates to toy pistols and has for its object to provide a toy of such class, with means for exploding paper caps and further with means for projecting a stream of water substantially simultaneously with the exploding of the caps.

15 A further object of the invention is to provide a toy pistol in a manner as herein-after set forth, with means for positioning a detonating charge in the path of a firing lever to be exploded during the cocking of said lever.

20 Further objects of the invention are to provide a toy pistol which is simple in its construction and arrangement, strong, durable, convenient in its use and inexpensive 25 to manufacture.

With the foregoing and other objects in view the invention consists of the novel construction, combination and arrangement of parts as hereinafter more specifically described and illustrated in the accompanying drawings, wherein is shown an embodiment of the invention, but it is to be understood that changes, variations and modifications can be resorted to which come within the 35 scope of the claim hereunto appended.

In the drawings wherein like reference characters denote corresponding parts throughout the several views:—Figure 1 is a side elevation of a toy pistol in accordance 40 with this invention. Fig. 2 is an elevation illustrating the mechanism of the pistol. Fig. 3 is a cross sectional view, on line X X, Fig. 1, and Fig. 4 is a cross sectional view of a modification.

45 Referring to the drawings in detail the pistol includes a supporting section and an inclosing section. The said supporting section consists of a body portion 1, having an extension 2 to represent a part of the barrel 50 of the pistol and further having an extension 3 to provide a section of the handle of the pistol. The supporting section has in the inner face of the extension 3 a recess 4 with which communicates a groove 5, the latter extending from the recess 4, through the body portion 1 and to the free end of

the extension 2. The groove 5 is curvilinear in contour and is adapted to have mounted therein a flexible tube 6, which communicates with a hollow spherical member 7 providing the water reservoir. The member 7 is seated in the recess 4.

Fixed in the body portion 1 is a pin 8, upon which is revolvably mounted a disk 9, having a toothed edge 10 and arranged 65 against said disk 9 and upon the pin 8 is a coil strip 11 which is in the form of the ordinary paper cap strip and the free end of said strip, which as indicated at 12 extends up between a pair of guides 13 and is 70 arranged behind an abutment 14. As is well known the paper cap strip has arranged therein, at equally distant points, detonating charges and the disk 9 is capable of being shifted so that a detonating charge 75 will be positioned at the abutment 14 and in the path of the hammer whereby when the trigger is pulled the hammer will strike the paper strip and explode the charge.

The disk 9 is shifted by a spring pressed 80 pawl 15, which has a nose 16, engaging teeth 10. The pawl 15 rests upon a supporting pin 17, which is carried by the body portion 1, and bearing against said pawl is a spring 18, secured to a pin 19 attached to 85 the body portion 1 of the supporting section.

Secured to the inner face of the body portion 1 of the supporting section, and rearwardly with respect to the pin 8, is a pivot 90 20, upon which the lower portion of a hammer 21 is pivoted. The pawl 15 is pivotally connected to the hammer as at 22. The hammer 21 has a striking head 23, and a finger piece 24, to facilitate the cocking of 95 the hammer. The rear of the hammer 21, near the lower portion thereof, has a rearward extension 24, which bears against a flat spring 25 secured at one end, as at 26, on a stud 27 which is carried by the extension 3. The cocking of the hammer 21 is against the action of the spring 25. The bottom edge of the hammer 21 has a concave notch 28 into which extends the nose 29, of a trigger 30, the latter being mounted upon 100 a pivot 31, secured to the body portion 1, below the groove 5.

In the foregoing construction and arrangement of parts, it is obvious when the hammer 21 is cocked the pawl 15 will be 110 pulled rearwardly turning the disk 9 upon the pin 8, whereby the paper cap strip car-

rying the detonating charges will shift up through the guides 13. The shifting movement of the strip 12 will be discontinued when the hammer has been cocked. When the hammer is actuated through the medium of the spring 25 when the trigger 30 is shifted, the pawl 15 will be moved forward to a position to engage in the teeth 10 when the hammer is cocked again.

- 10 The closure section consists of a body portion 32, an extension 33 which forms the other section of a handle and an extension 34 which forms the other section of a barrel. The closure section is mounted against
- 15 the supporting section and maintained in position by the hold fast devices 35. The extension 33 of the closure section is hollowed so as to receive a part of the spherical member 7 and said extension 33 has a
- 20 push button 36, which when forced inwardly, will cause the projecting of a stream of water from the member 7 outwardly through the tube 6. The projecting of the stream of water can be accomplished simultaneously with the firing of a detonating charge by the striking head 23 of the hammer.
- 25

The body portion 1 of the supporting section, is offset to represent a portion of the cylinder of a pistol, as at 37, and the body portion 32 of the closure section is provided with a pair of parallel strips 38, 39, into

which is arranged a slide 40 representing the other half of the cylinder of the pistol.

The modification shown in Fig. 4 consists of a pair of push buttons 36 in lieu of a single push button.

What I claim is:—

A toy pistol comprising a body portion having a depending handle provided there- 40 in near its lower end with a spherical recess, said handle further having the lower end thereof formed with an opening communicating with the said recess, a recipro- 45 catory push button extending through said opening and connected to said handle, a hollow spherical member arranged in said recess and constituting a water reservoir 50 and adapted to be compressed by said push button whereby water is expelled therefrom, said pistol body having an exteriorly ar- 55 ranged groove of compound curvature opening at one end into said recess and opening at its other end at the forward end of said body, a tube snugly fitting throughout said groove and communicating at one end with said member and opening at its other end at the forward end of said groove.

In testimony whereof I affix my signature in presence of two witnesses.

CHARLES W. KALLENBAUGH.
